US00D344928S

United States Patent [19]**Vinciarelli et al.**[11] **Patent Number:** **Des. 344,928**[45] **Date of Patent:** **** Mar. 8, 1994**[54] **PACKAGE FOR DC-DC POWER
CONVERTER OR RELATED CIRCUITRY**[75] **Inventors:** **Patrizio Vinciarelli, Boston; Fred M. Finnemore, North Reading, both of Mass.**[73] **Assignee:** **VLT Corporation, San Antonio, Tex.**[**] **Term:** **14 Years**[21] **Appl. No.:** **916,350**[22] **Filed:** **Jul. 17, 1992****Related U.S. Application Data**

[63] Continuation-in-part of Ser. No. 809,412, Dec. 17, 1991.

CLAIM

The ornamental design for a package for DC-DC power converter or related circuitry, as shown and described.

DESCRIPTION

FIG. 1 is a perspective view of a package for a DC-DC power converter or related circuitry;

FIG. 2 is a bottom plan view thereof;

FIG. 3 is a side elevational view thereof, the opposite side being mirror image;

FIG. 4 is a top plan view thereof;

FIG. 5 is an end elevational view thereof;

FIG. 6 is another end elevational view thereof, this end being opposite the end of FIG. 5;

FIG. 7 through 12 illustrate another embodiment, where the descriptions of FIGS. 7 through 12 correspond to the descriptions of FIGS. 1 through 6, respectively;

FIGS. 13 through 18 illustrate another embodiment, where the descriptions of FIGS. 13 through 18 correspond to the descriptions of FIGS. 1 through 6, respectively;

FIGS. 19 through 24 illustrate another embodiment, where the descriptions of FIGS. 19 through 24 correspond to the descriptions of FIGS. 1 through 6, respectively;

FIGS. 25 through 30 illustrate another embodiment, where the descriptions of FIGS. 25 through 30 correspond to the descriptions of FIGS. 1 through 6, respectively; and,

FIGS. 31 through 36 illustrate another embodiment, where the descriptions of FIGS. 31 through 36 correspond to the descriptions of FIGS. 1 through 6, respectively.

Drawing No. 200-0500 (Tower Electronics).

Design Data Sheet-VI-100 Series (Vicor).

1991 Product Catalog (Vicor).
